UNITED STATES PATENT OFFICE.

ALBERT TILTON, OF NEW HAVEN, CONNECTICUT, ASSIGNOR TO WINCHESTER REPEATING ARMS CO., OF NEW HAVEN, CONNECTICUT, A CORPORATION.

FRONT SIGHT FOR FIREARMS.

SPECIFICATION forming part of Letters Patent No. 712,863, dated November 4, 1902.

Application filed June 23, 1902. Serial No. 112,913. (No model.)

To all whom it may concern:

Be it known that I, ALBERT TILTON, of New Haven, in the county of New Haven and State of Connecticut, have invented a new and useful Improvement in Front Sights for Firearms; and I do hereby declare the following, when taken in connection with the accompanying drawings and the numerals of reference marked thereon, to be a full, clear, and exact 10 description of the same, and which said drawings constitute part of this specification, and represent, in—

Figure 1, a view in rear elevation of one form which a sight containing my improvement may assume; Fig. 2, a view thereof in side elevation; Fig. 3, a view in rear elevation of another form which my improved sight may assume; Fig. 4, a view thereof in side elevation.

20 My invention relates to an improvement in front sights for firearms, the object being to produce at a low cost a simple, compact, durable, and convenient sight having a light-colored sight-point.

25 With these ends in view my invention consists in a front sight for firearms comprising a sight proper provided with a light-colored metal sight-point composed of a small body of the metal directly cohered to the sight, so as to constitute a virtually integral part thereof.

In carrying out my invention as shown in Figs. 1 and 2 of the drawings I locate a small globule-like light-colored sight-point 2 upon 35 the rear end of the horizontal rib 3, formed integral with the upper edge of the leaf 4 of the sight, which also comprises a transversely-arranged dovetail 5, designed to enter a corresponding groove formed transversely in the 40 top of the gun-barrel. The sight-point is applied to the metal of the sight proper, to which it is directly cohered, so as to be virtually integral therewith. For the sight-point I preferably use pure tin, though I may use other light-colored metals or light-colored compositions—such, for instance, as solder, spelter, &c. In carrying out my invention the sight proper is preferably finished and blued. Then the bluing is removed by buffing, filing, or otherwise from the rear end of 50 the sight-rib 3. The exposed metal is then

treated with acid to clean the metal, so as to secure a surface to which another metal will cohere. The sight is then dipped into the bath of the sight-point metal, whatever it 55 may be, so as to expose its cleaned and acid-treated surface thereto. When now the sight is lifted from the bath, a small globule-like mass of the sight-point metal will be found adhered to the sight. This little mass of 60 metal hardens before it can drop back into the bath and forms a symmetrical globule-like sight-point which coheres directly to the metal of the sight proper in such a way that it virtually becomes an integral part 65 thereof. If desired, it can afterward be trimmed, shaped, and finished. It takes the place of the ivory sight-points which heretofore have very generally been employed and which are not only expensive, but frail.

In the construction shown by Figs. 3 and 4 of the drawings a similar sight-point 6 is applied in the same way to the upper corner of the rear edge of a pivotal leaf-like sight 7, turning upon the pin 8, mounted in a dovetail base 9.

Of course a sight-point such as described may be applied to a great variety of gun-sights; but the forms shown will sufficiently illustrate my invention. I would therefore 80 have it understood that I do not limit myself to the construction shown and described, but hold myself at liberty to make such alterations therein as fairly fall within the spirit and scope of my invention.

Having fully described my invention, what I claim as new, and desire to secure by Letters Patent, is—

As a new article of manufacture, a front sight for firearms consisting of a sight proper 90 provided with a sight-point composed of a small body of light-colored metal directly adhered to the external face of the sight so as to constitute a virtually integral part thereof.

In testimony whereof I have signed this 95 specification in the presence of two subscribing witnesses.

ALBERT TILTON.
